RAILWAY CROSSING

Thomas A. Ratkowski, Chicago Heights, Ill., assignor to American Brake Shoe Company, a corporation of Delaware

Application August 31, 1942, Serial No. 456,789

13 Claims. (Cl. 246—464)

The present invention relates to railway crossings and more particularly to railway crossings of the box type.

Among the objects of the present invention is to provide a railway crossing of the box type in which the base, the wall members upstanding from said base, and the horizontal web portion bridging the spaces between the wall members and providing intersecting flangeways and tread surfaces, are all formed in one integral casting designed appropriately for optimum foundry practice and uniform heat treatment that is resorted to for developing a desired structure in the metal, for instance, when manganese steel is used.

Another object of the present invention is to provide a railway crossing of the box type in which the base is of continuous construction, except for the provision of openings necessary for the removal of core forming material from the inside of the box structure and to provide for quenching and other necessary heat treatment; thus assuring proper load distribution at the crossing intersection.

Still a further object of the present invention is to provide a railway crossing of the box type in which upstanding walls are provided at desired locations within the box structure which act as load sustaining columns serving as substantial continuations of the webs of adjacent running rails and to distribute wheel loads over the entire base and to the supporting ties.

More particularly the present invention is directed to railway crossing structures of the box type in which the load sustaining webs or columns are disposed in interconnecting relation to the outer walls forming the box structure, and which in themselves form box structures within the box formation defining the crossing structure.

As a further desideratum of the invention, such load sustaining columns or webs are disposed in substantial parallel relation at or adjacent the tread surfaces defined by the flangeways developed in the bridging web forming the top portion of the crossing structure.

As a further object of the present invention, said load sustaining columns may assume further importance in the structure involved, in that the same may be formed as continuations below one or more of the said intersecting flangeways.

Other objects, features, capabilities and advantages are comprehended by the invention, as will later appear and as are inherently possessed thereby.

Referring to the drawings—

Figure 1 is a top plan view of a crossing struc-

ture embodying the novel features of construction of the present invention;

Figure 2 is a view in cross section taken in the plane represented by line 2—2 of Figure 1 of the drawings;

Figure 3 is a top plan view of a modified form of crossing structure embodying additional features of construction comprehended by the present invention;

Figure 4 is a view in cross section taken in the plane represented by line 4—4 of Figure 3;

Figure 5 is a top plan view of a modified form of crossing structure embodying additional features of construction comprehended by the present invention;

Figure 6 is a view in cross section taken in the plane represented by line 6—6 of Figure 5 of the drawings;

Figure 7 is a view in cross section taken in the plane represented by line 7—7 of Figure 5 of the drawings; and

Figure 8 is a view in cross section taken in the plane represented by line 8—8 of Figure 5 of the drawings.

Referring now more in detail to the drawings, a railway crossing selected to illustrate the present invention, is shown in Figure 1 as comprising a casting of integral construction having a central body portion generally referred to as 2, and the four crossing branches 4, 6, 8 and 10 extending from said body portion and adapted to connect the said body portion with running rails of a track in which the crossing is used.

The crossing structure is of the box type, including a base 12 and an upper bridging web 14 interconnected by upstanding load sustaining walls generally referred to as 16 and which have a formation as hereinafter more fully set forth. The top bridging web 14 is formed with intersecting flangeways 18 and 20 comprising depending ribs 22 terminating short of the base 12, and providing crossing corners 24, 26, 28 and 30 developed by said flangeways.

The load sustaining walls 16 more particularly take the form of transverse wall sections 32, 34, 36 and 38 intersecting the ribs forming the flangeways for the branches 4, 6, 8 and 10, respectively, and which wall sections are interconnected by the substantially diagonally disposed wall sections 40, 42, 44 and 46 extending between the adjacent branches of the crossing structure and being formed integral with the wall sections heretofore identified, as well as others such as 48, which complete the crossing structure and provide a suitable arrangement for the connection of the

running rails connected to said crossing branches.

The embodiment as shown in Figure 1 is further characterized in that additional load supporting columns or walls are provided which extend inwardly from the walls hereinbefore described and which form with such walls, inner housing structure so located with respect to the flangeways and the adjacent tread surfaces, such as 50, as to efficiently and effectively distribute the wheel loads of trucks passing thereover. The formation for such additional load sustaining webs at the crossing intersection between adjacent branches is much the same and involves the provision of the upstanding webs such, for example, as 52 and 54, joined integrally adjacent the crossing corner 24 and interconnecting the base 12 with the ribs 22 forming the flangeways 18 and 20. These load sustaining walls or columns are disposed substantially beneath the tread surfaces defining the crossing corner 24, and are effective in the proper distribution of wheel loads passing over the crossing. The embodiment of Figure 1, as suggested above, includes similar load sustaining webs which extend inwardly toward the other crossing corners between adjacent branches to provide the inner box structure hereinbefore mentioned.

In order to facilitate the removal of the core forming material from the interior compartments of the crossing structure and to permit proper heat treatment of the casting, one or more openings such as 56 may be provided in the base 12. It is also understood that the crossing herein exemplified may be formed to provide for any desired angle of intersection of the crossing branches which are connected to the running rails of the track in which the crossing is used.

Figure 3 represents a modification of the structure disclosed in Figure 1 of the drawings, for which use may be found under certain circumstances. The structure as a whole, however, conforms to that shown in Figure 1 of the drawings, the modification consisting in the provision of additional load sustaining webs or columns 68 and 60 which interconnect and are formed integral with the walls 54 of crossing corners 24, 26, and 28, 30, respectively, the said load sustaining walls or columns intersecting the flangeway 20 and extending below and forming a connection between the rib 22 forming said flangeway and the base 12. This form of structure provides additional means for distribution of wheel loads and provides means for interconnecting and tying together the load sustaining walls 54. Because of the said load sustaining walls 58 and 60 it has been found desirable to provide openings such as 62 in the load sustaining walls 52 in order to permit removal of core forming material from the interior compartments of the crossing structure and for proper heat treatment. These openings, however, are of such a size that no material weakening of the crossing structure at the crossing corner results.

Figure 5 represents a further modification of the railway crossing shown in Figure 1 of the drawings, the same embodying essentially the structure therein disclosed except for the incorporation of additional load sustaining walls or columns substantially for the purposes described in connection with the modification shown in Figure 3.

In this embodiment the said crossing structure incorporates the load sustaining webs 64 and 66 formed integral with the walls 52 and 54 and in-

tersecting substantially beneath the crossing corner 24. The load sustaining wall 66 corresponds identically to the load sustaining wall 58 of the modification shown in Figure 3, forming a continuation of the walls 54 and interconnecting the rib forming the flangeway 20 with the base 12 directly therebeneath. The load sustaining wall or column 64 is formed as a continuation of the walls 52 and serves to interconnect the rib forming the flangeway 18 with the base 12 directly therebeneath. This form of construction serves to tie the crossing corners 24, 26 and 30 more effectively and provides essentially for the proper distribution of wheel loads at said crossing corners, and particularly crossing corner 24. As in the embodiment shown in Figure 3 of the drawings, the walls 52 and 54 may be provided with openings such as 68 to permit of the removal of core forming material and for proper heat treatment.

While there is described herein and upon the drawings shown an illustrative embodiment of the invention, it is to be understood that the invention is not limited thereto but may comprehend other constructions, arrangements of parts, details and features without departing from the spirit of the invention.

What is claimed is:

1. A railway crossing structure comprising a member formed with a box-like centrally disposed body portion and a plurality of crossing branches for connection to adjoining running rails, said crossing structure including a base, a top portion in the form of a bridging web having intersecting flangeways and tread surfaces, said flangeways being developed as downwardly presented ribs terminating short of said base, a substantially continuous web connecting said base and top portion and forming the box-like central body portion, said web being spaced throughout from the junction of said flangeways, and inner webs forming inner box-like portions with said first mentioned web and connecting the base and bridging web substantially beneath at least each wheel bearing tread surface and extending substantially from said first mentioned web to the intersection of said flangeways.

2. A railway crossing structure as described in claim 1, in which webs interconnecting with certain of said last-named webs are provided in substantially parallel relation to form reinforcement beneath one of the ribs of said flangeways at the junction thereof.

3. A railway crossing structure as described in claim 1, in which webs interconnecting with certain of said last-named webs are provided in angular relation to one another at one of the crossing corners formed by said flangeways and extending between said second mentioned web beneath the ribs of said flangeways at the junction thereof.

4. A railway crossing structure as described in claim 1, in which a web is provided to form a reinforcement beneath at least one of the ribs of said flangeways at the junction thereof.

5. A railway crossing structure comprising a member formed with a box-like centrally disposed body portion and a plurality of crossing branches for connection to adjoining running rails, said crossing structure including a base, a top portion in the form of a bridging web having intersecting flangeways and tread surfaces, said flangeways being developed as downwardly presented ribs terminating short of said base, a substantially continuous web connecting said base and top portion and forming the box-like central body por-

tion, said web being spaced throughout from and having substantially diagonally disposed portions in opposed relation to the crossing corners formed by said flangeways, and inner webs forming inner box-like portions with said first mentioned web and connecting the base and bridging web substantially beneath at least each wheel bearing tread surface and extending substantially from said first mentioned web to the intersection of said flangeways.

6. A railway crossing structure comprising a member formed with a box-like centrally disposed body portion and a plurality of crossing branches for connection to adjoining running rails, said crossing structure including a base, a top portion in the form of a bridging web having intersecting flangeways and tread surfaces, said flangeways being developed as downwardly presented ribs terminating short of said base, a substantially continuous web connecting said base and top portion and forming the box-like central body portion, said web being spaced from the junction of said flangeways, and inner webs forming inner box-like portions with said first-mentioned web and connecting the base and bridging web substantially beneath each of the crossing corners formed by said flangeways and extending substantially from said first mentioned web to the intersection of said flangeways.

7. A railway crossing structure as described in claim 6, in which webs interconnecting with certain of said last-named webs are provided in substantially parallel relation to form reinforcement beneath one of the ribs of said flangeways at the junction thereof.

8. A railway crossing structure as described in claim 6, in which webs interconnecting with certain of said last-named webs are provided in angular relation to one another at one of the crossing corners formed by said flangeways and extending between said second mentioned webs beneath the ribs of said flangeways at the junction thereof.

9. A railway crossing structure as described in claim 6, in which a web is provided to form a reinforcement beneath at least one of the ribs of said flangeways at the junction thereof.

5 10. A railway crossing structure comprising a member formed with a centrally disposed body portion and a plurality of crossing branches for connection to adjoining running rails, said crossing structure including a substantially continuous base, a top portion in the form of a bridging web having intersecting flangeways and tread surfaces, said flangeways being developed as downwardly presented ribs terminating short of said base, a substantially continuous web connecting 15 said base and top portion formed in part by portions extending between the adjacent crossing branches and in part by interconnecting portions disposed beneath the ribs of said flangeways, said substantially continuous web being spaced throughout from the junction of said flangeways, and webs disposed between said base and top portion substantially beneath each of the corners formed by said flangeways.

11. A railway crossing structure as described in claim 10, in which webs interconnecting with certain of said last-named webs are provided in substantially parallel relation to form reinforcement beneath one of the ribs of said flangeways at the junction thereof.

30 12. A railway crossing structure as described in claim 10, in which webs interconnecting with certain of said last-named webs are provided in angular relation to one another at one of the crossing corners formed by said flangeways and 35 extending between said second mentioned webs beneath the ribs in said flangeways at the junction thereof.

13. A railway crossing structure as described in claim 10, in which a web is provided to form a reinforcement beneath at least one of the ribs of said flangeways at the junction thereof.
